US0D1070785S

(12) **United States Design Patent** (10) **Patent No.:** **US D1,070,785 S**
(45) **Date of Patent:** **** Apr. 15, 2025**

(54) **MATABLE CONNECTOR**

(71) Applicant: **B.E. Meyers & Co., Inc.**, Redmond, WA (US)

(72) Inventor: **Thomas Alldredge**, Seattle, WA (US)

(73) Assignee: **B.E. Meyers & Co., Inc.**, Redmond, WA (US)

(**) Term: **15 Years**

(21) Appl. No.: **29/917,916**

(22) Filed: **Nov. 22, 2023**

(51) LOC (15) Cl. **13-03**

(52) U.S. Cl.

USPC **D13/146**

(57) **CLAIM**

The ornamental design for a matable connector, as shown and described.

DESCRIPTION

FIG. 1 is a first perspective view of a design for the matable connector;

FIG. 2 is a second perspective view of the design therefor;

FIG. 3 is a front side view of the design therefor;

FIG. 4 is a rear side view of the design therefor, opposite the front side view;

FIG. 5 is a first side view of the design therefor;

FIG. 6 is a second side view of the design therefor, opposite the first side view;

FIG. 7 is a top plan view of the design therefor;

FIG. 8 is a bottom plan view of the design therefor;

FIG. 9 is a perspective of the section view along the cut line shown in FIG. 3; and,

FIG. 10 is a section view along the cut line shown in FIG. 3.

The broken lines in the drawings depict portions of the matable connector that form no part of the claimed design.

1 Claim, 3 Drawing Sheets
